CLAIM

The ornamental design for a electrical receptacle, as shown and described.

DESCRIPTION

FIG. 1 is a perspective view of a electrical receptacle showing my new design;

FIG. 2 is a front view thereof;

FIG. 3 is a back view thereof;

FIG. 4 is a right side view thereof, the left side view being a mirror image thereof;

FIG. 5 is a top view thereof; and,

FIG. 6 is a bottom view thereof.

In the drawings, the broken lines are for the purpose of illustrating portions of the article that form no part of the claimed design.

1 Claim, 3 Drawing Sheets(56)
